SIGNAL CONTROLLED KEYING CIRCUIT

Charles N. Gillespie, Jr., Brooklyn, N. Y., assignor
to Radio Corporation of America, a corporation
of Delaware

Application March 29, 1941, Serial No. 385,809

9 Claims. (Cl. 178—66)

This invention relates to the remote control of electrically operated devices, such as relays, by means of a signal of radio or audio frequency. More specifically, it relates to a high speed keyer circuit where a direct current relay or other response device must be used.

It is an object of my invention to provide a means for utilizing a single frequency for signaling purposes and means for discriminating against other frequencies.

Another object is to provide a means for utilizing marking and spacing signals to alternately ignite and extinguish a gaseous discharge tube, and to render the ignition period concurrent with either the marking signal or the spacing signal.

In carrying out my invention I have found that a signal of proper frequency may be employed to produce a high voltage in a series resonant circuit associated with a gas discharge tube of the triode type. This high voltage is preferably applied negatively to the cathode of such a tube in order to ignite the same. The resulting discharge is used to pass current in an anode circuit which may include a relay of any suitable type. Connected to the output circuit of the gas triode I also employ an auxiliary discharge tube which may be of the vacuum type, if desired, for momentarily reducing the anode voltage of the gas triode to a point below its extinction potential. The control electrode of the auxiliary tube, and the cathode of the gaseous discharge tube, are both subject to control by the signal.

In circuits heretofore known an alternating voltage of commercial frequency is customarily used on the plate of the gas triode. Such practice eliminates the need for auxiliary extinguishing devices, but results in a circuit useful only for low speed signaling.

My invention will now be described in more detail, reference being made to the accompanying drawing the sole figure of which shows a preferred circuit arrangement.

The circuit arrangement as shown includes input terminals 1 and 2 for impressing thereon of suitable signals. The gaseous discharge tube 4 possesses an anode A, a control grid G connected to an intermediate point on a voltage divider 13, 14, and a cathode K. A series resonant circuit comprising the capacitor 3 and inductance 5 is connected across the terminals 1 and 2 and at the junction point between capacitor 3 and inductance 5 connection is made to the cathode K in the tube 4.

10 A source of direct current operating potential 15 is connected through resistor 11 and relay 7 to the anode A in tube 4. The negative side of the source 15 is directly connected to the input terminal 2, and through inductance 5 (and shunt resistor 6) to the cathode K. A fixed bias potential for the control grid G is derived from a suitable connection thereof to the voltage divider 13, 14. This bias potential is somewhat positive with respect to the cathode, but is safely below the ignition point.

The auxiliary tube 10, which is used for extinguishing the tube 4, is preferably of the tetrode type. Its cathode is connected to the negative terminal of source 15. Its anode is connected to the junction between relay 7 and resistor 11. Its screen grid is connected to the positive terminal of the source 15 and its control grid is connected to a grid leak resistor 9 and shunt condenser 8 which are connected to the adjustable tap on the voltage divider 6.

15 When a signal of the resonant frequency of inductance 5 and capacitance 3 is impressed on terminals 1 and 2, the signal voltage appearing across inductance 5 will be high. Negative peaks of this voltage are applied to the cathode K of the gas triode 4. The resulting increase of potential difference between the cathode K and control grid G (carried at a fixed bias) causes the tube 4 to ignite and to conduct a current. The resulting plate current will operate the relay 7. Signals of frequencies other than the resonant frequency of inductance 5 and capacitance 3 will have a negligible effect on the circuit, since the voltage across inductance 5 will be small for all frequencies except the resonant frequency.

20 The high voltage appearing across inductance 5 when a signal of the resonant frequency is applied to the circuit, is also applied to the grid of the vacuum tube 10, which acts as a grid leak detector. This will cause the average plate current of this tube to decrease to a value which will cause a very small voltage drop across the resistor 11. The total drop across resistor 11 due to the plate current of tube 10 and tube 4 will not be so large as to cause the plate voltage of tube 4 to fall to the extinction potential. Therefore, the conduction of tube 4, which was started by the signal, will be sustained.

25 The value of resistor 11 and the position of the arm of potentiometer 6 should be adjusted so that the decrease in plate current of tube 10 with application of the signal, will be at least twice the plate current of tube 4. This is to pre-

vent the plate current of tube 4 from lowering its plate voltage to the extinction point.

Upon removal of the signaling frequency, vacuum tube 10 will draw full plate current, since a substantially zero bias is then applied to its grid through the grid leak resistor 9. This increased plate current will cause an increase in voltage drop across resistor 11, whose value is chosen so that this drop will lower the potential on the plate of tube 4 below the extinction point. This will cause tube 4 to cease conducting current and the relay 7 will become de-energized.

The value of potentiometer 6 should be made as high as possible so that the "Q" of the inductance 5 will not be seriously lowered.

This circuit arrangement has been found to be very dependable in responding to relatively weak signals of the frequency to which the resonant circuit 3, 5 is selective. Furthermore, it requires only a small variation in the signal voltage to control the tube 10. The control potential as applied to the grid of tube 10 is varied between a substantially zero bias in the absence of the signal and a cut-off bias in the presence of the signal.

It will be understood by those skilled in the art that my invention is capable of use in connection with other devices than the relay 7 and that the circuit arrangements may be varied in certain particulars without departing from the spirit of the invention.

I claim:

1. In a keying system, a gaseous discharge tube having a cathode, an anode and a control grid; means normally subjecting said control grid to a negative biasing potential with respect to said cathode, a circuit resonant to the frequency of certain keyed signals by which the moments of ignition and extinction of said tube are to be controlled; means including a connection from a suitable point on said resonant circuit to the cathode of said tube whereby a signal voltage appearing across a reactive element of said resonant circuit causes said tube to ignite; an anode circuit for said tube including a utilization device, an impedance, a direct current source, and the inductive element of said resonant circuit; and means including an auxiliary discharge tube for causing the moments of extinction of said gaseous tube to be controlled by said signals, said auxiliary tube being powered by said source, and having a control grid normally biased to permit current flow in the absence of signals, and subject to a cut-off bias in the presence of signals.

2. In a system according to claim 1, the combination so defined in which said utilization device is constituted as an electromagnetic relay.

3. In a system according to claim 1, the combination so defined in which the discharge tube of the last said means is constituted as a tetrode having its screen grid subjected to a positive potential derived from said direct current source.

4. In a signal-controlled circuit arrangement for actuating an electromagnetic relay, a tube having a gaseous discharge path in series with the winding of said relay; an inductance, a direct current source and an impedance also in circuit with said winding and said discharge path; a pair of signal input terminals connected through a capacitor to the terminals of said inductance, said capacitor and inductance forming a series resonant circuit tuned to the frequency of the applied signals; an igniter grid in said tube; voltage divider connections from said

source to said grid; discharge extinction means constituted by an auxiliary tube having its space current path connected across from the junction of said impedance and said relay winding to the negative terminal of said source; and a voltage divider connected across the terminals of said inductance, this voltage divider having an adjustable tap connected through a grid leak to a control grid in said auxiliary tube, whereby, in the absence of signals a zero bias is applied to said grid, such that the auxiliary tube becomes conductive and causes the gaseous discharge in the first said tube to be extinguished.

5. In a keying system, a gaseous discharge tube having a cathode, a control grid, and an anode; an output circuit for said tube, said output circuit including an inductance connected to said cathode, a direct current source, an impedance, and a utilization device connected to said anode; a pair of input terminals one of which is directly connected to the negative terminal of said source and the other of which is coupled through a capacitor to the junction between said cathode and said inductance, said capacitor and said inductance forming a series resonant circuit tuned to a predetermined frequency of signals applied to said input terminals; a voltage divider connected in shunt with said inductance; a second voltage divider connected across the terminals of said direct current source; gas discharge extinction means constituted by a vacuum discharge tube the anode of which is connected to the junction between said impedance and said utilization device, and the cathode of which is connected to the negative terminal of said direct current source; and two control grid circuits each connected to an intermediate point on an appropriate one of said voltage dividers, the first said voltage divider being arranged to supply a variable bias to the control grid of said vacuum tube and the second said voltage divider being arranged to supply a fixed bias to the control grid of said gaseous tube.

6. Apparatus for actuating an electromagnetic relay in response to tone-modulated marking and spacing signals, said apparatus comprising a gaseous discharge tube the discharge path of which is in circuit with the winding of said relay and is powered by a direct current source connected at the positive terminal through a resistor to the winding of said relay and thence to the anode of said tube, the cathode of said tube being in circuit with the negative terminal of said source, a tuned signal input circuit resonant to the tone frequency of said signals, said input circuit including connections to said cathode and to a control electrode in said tube, and discharge extinguishing means constituted by an auxiliary tube the discharge path of which is in circuit between the anode and cathode of said gaseous discharge tube, said means including in said auxiliary tube a control grid connected to an adjustable tap on a voltage divider which shunts an inductive portion of said resonant input circuit, and said means being operative in response to the presence of signals to apply a cut-off bias to said control grid and upon cessation of signals to render said auxiliary tube conductive, thereby to reduce the potential drop in said gaseous discharge path to the extinction point.

7. In a circuit arrangement for utilizing a gaseous discharge tube to key a current through the winding of a relay in response to the reception of tone modulated signals, where such signals may be varied as to the duration of their

marking and spacing elements, said circuit arrangement having an auxiliary tube the discharge path of which is subject to control by said signals, the method of igniting and extinguishing said gaseous discharge tube which comprises resonating the input circuits for both said tubes at the tone frequency of said signals, causing the gaseous discharge tube to be ignited and the auxiliary tube to be blocked simultaneously upon reception of the tonal wave front of each said signal, and causing said gaseous discharge tube to be extinguished by the unblocking of said auxiliary tube at the tonal wave termination of each said signal.

8. In a keying circuit arrangement, a direct current relay to be energized upon reception of a tone modulated marking signal, a gaseous triode tube having its discharge path in series with the winding of said relay, an auxiliary tube having its discharge path in shunt with a portion of the circuit of said relay and gaseous triode, a signal control circuit including resonant elements tuned to the signaling tone frequency, and connections between said resonant elements and certain electrodes of both said tubes such that the gaseous triode is ignited at the commencement of a marking signal and simultaneously said auxiliary

tube is blocked, and such that the unblocking of said auxiliary tube upon cessation of a marking signal causes the voltage drop in the gaseous triode to be reduced below the critical voltage necessary to sustain ignition therein.

9. In a keying system responsive to the reception of tone modulated signals, a series-resonant circuit connected across two input terminals of said system; a gaseous discharge tube having a cathode connected to a junction between capacitive and inductive elements of said series-resonant circuit, and having a cathode-to-anode circuit including the inductive element of said series-resonant circuit, also a direct current source, a resistor, and a device responsive to the flow of current therethrough; an auxiliary discharge tube having its cathode-to-anode circuit inclusive of said source and said resistor; and control means for said auxiliary tube arranged to block the same in response to the up-building of signal potentials across said inductive element, said control means being operable upon termination of the tonal signal wave to render said auxiliary tube conductive and thus to cause extinction of said gaseous tube.
